UNITED STATES PATENT OFFICE.

PATRICK D. HINES, OF SUMMIT STATION, OHIO.

PUMP.

SPECIFICATION forming part of Letters Patent No. 337,402, dated March 9, 1886.

Application filed December 2, 1885. Serial No. 184,528. (No model.)

To all whom it may concern:

Be it known that I, PATRICK D. HINES, a citizen of the United States, residing at Summit Station, in the county of Licking and State 5 of Ohio, have invented a new and useful Improvement in Pumps, of which the following is a specification.

My invention relates to improvements in double-cylinder pumps; and the objects of my 10 improvements are to produce a double-cylinder pump adapted for use in pumping the water either from the top or bottom of a well, or to draw water from both points. I accomplish these objects in the manner illustrated 15 in the accompanying drawings, in which—

Figure 1 is a vertical section of my improved pump, and Fig. 2 is a front elevation of the same.

Similar letters refer to similar parts throughout the several views.

A represents the stock or main body of the pump, having a barrel, b, and a barrel, c. The barrel b is of the usual length, and may be continued to the required length, which is 25 preferably near the bottom of the well, by joining to that portion of the stock, in the usual manner, a second stock. The barrel c extends only a short distance below the platform of the well, and has its lower end closed. 30 At a short distance below the top of the pump these two barrels b c are made to communicate by means of a transverse hole or cut extending through the partition dividing the barrels. The barrels are each provided with 35 the usual plunge-rod, having a sucker and valve on the lower end thereof.

The pump-handle g is made to project outwardly from above the top of the pump, and is pivoted or hinged to a bolt, h, made to extend between two upwardly-projecting plates, m, secured to the front and rear sides of the stock. The handle g is provided at points immediately above the barrels b c with vertical slots, within which are pivoted the upper 45 ends of metal hinging-plates k by means of short transverse bolts i i', the lower ends of said plates k being hinged or pivoted to the upper ends of the plunge-rods d d'.

Projecting outwardly through the side of

the stock from a point near the bottom of the 50 cylinder or barrel c and opening therein is a short tube, p, having on its inner end a valve, o, of any well-known form, and having fitted over its outer projecting end the upper end of a flexible pipe, e. This pipe e, which may 55 be of any desired length, extends downward, and has secured to its lower end, by means of a ring and staple, a block or suitable float, f.

A spout, n', of the usual form, is made to project outwardly from the front side of the 60 pump at a point opposite the center of the transverse cut n, with which it connects.

The pump being constructed as above described, the operation of the handle g in the usual manner will cause the plunge-rods to 65 rise and fall alternately, the rod d operating to draw the water in the usual manner from near the bottom of the well, the rod d' operating to draw only the surface-water, the flexible pipe e, through which the surface-water passes to the cylinder or barrel c, being kept from sinking but slightly below the surface of the water by means of the float f.

It is a well-known fact that at times the surface-water in a well becomes stagnant and unfit for use. This stagnant surface-water may be readily pumped off without disturbing the deeper water by withdrawing the bolt i, thus uncoupling the rod d from the handle, and allowing the rod d' to be operated alone. The 75 water drawn into either cylinder is allowed to escape through the cut n and out through a common spout, n'.

Having now fully described my invention, what I claim, and desire to secure by Letters 80 Patent, is—

A double-cylinder pump having one barrel upon a higher level than the other, in combination with a flexible pipe connecting with the lower end of the shorter pump-barrel, and a 90 float secured to the lower end of said flexible pipe, substantially as and for the purpose specified.

PATRICK D. HINES.
